COOLING MEANS FOR CLUTCHES AND BRAKES

Achille Carlo Sampietro, known as Achilles Charles Sampietro, London, England, assignor to D. R. Robertson Limited, London, England, a company of Great Britain

Application June 30, 1950, Serial No. 171,312
In Great Britain July 4, 1949

4 Claims. (Cl. 310—105)

1

This invention relates to slip couplings for use as clutches or brakes for transmitting or restraining rotary motion, and of the kind having a rotary member which is heated as a result of operation of the coupling and which is accommodated in a fixed casing.

A first object of this invention is to provide such a coupling with self-contained cooling means employing the surrounding atmosphere as the cooling medium.

A second object is to provide in an electromagnetic coupling a construction of rotary member which consists partly of magnetic material and partly of a metal of relatively high heat conductivity so as to increase the heat dissipation capacity of the rotary member.

A third object is to prevent the parts of such a built-up rotary member from becoming loose with respect to one another as a result of changes of temperature.

According to this invention, in a coupling of the kind hereinbefore specified, the rotary member is provided at at least one of its sides with impeller vanes co-operating with a centrifugal fan chamber formed in the side of the fixed casing, the fan chamber is provided with a plurality of delivery ducts distributed around the casing and having outlets shaped to discharge air in directions having components directed radially inwards against the periphery of the rotary member, and the casing is provided with exhaust ports which are distributed around the casing in alternation with the outlets of the delivery ducts. The periphery of the rotary member is preferably provided with circumferentially disposed cooling fins.

When the coupling is of the electromagnetic type and the rotary member includes an annular armature, the rotary member may be built up from a drum of a material of relatively high heat conductivity, e. g. an aluminium or magnesium base alloy (hereinafter termed a light alloy), carrying the impeller vanes and provided with integral circumferential cooling fins, this drum being shrunk onto the annular armature.

In such a built-up construction embodying a light alloy drum having a cylindrical bore into which the annular armature is fitted, the armature may be locked to the drum by rivets, consisting wholly or largely of copper and in a hard-drawn condition, disposed parallel to the coupling axis through bores in an end wall of the drum and in the armature.

One example of the invention as applied to an electromagnetic coupling of the eddy-current type will now be described, by way of example, with

2

reference to the accompanying diagrammatic drawings wherein:

Figs. 1 and 2 are sections taken on the lines 1—1 and 2—2 respectively in Fig. 3 and Fig. 3 is an end view of the coupling.

The driven coupling member 10 where the coupling is used as a clutch (or the stationary member 10 where the coupling is used as a brake), is an annular electromagnet of channel section 10 arranged with the channel opening radially outwards. The magnet contains an exciting coil 11 for connection to a D. C. source. At the periphery of each side wall of the channel is a ring of uniformly spaced pole-pieces 12, the numbers of pole-pieces in the two rings being the same. The pole-pieces of one ring are staggered with respect to those of the other. Each pole-piece includes a finger 13 projecting over the mouth of the channel to a distance such that the fingers of one ring 15 interlace with those of the other. All the pole faces lie in a common spherical belt 14.

The rotary member includes a hollow armature 15 enveloping the two rings of pole-pieces and fitted in a cylindrical bore in a light alloy rim 16 provided with circumferential cooling fins 17. This rim 16 is rigid with a light alloy flange 18, the rim and flange together forming a drum 20 coupled to a driving member. At each side of the rotary member near its periphery is a ring of radial-flow impeller vanes 20, which are integral with the rim 16.

A fixed casing 21 consists of two light alloy castings joined at a plane containing the coupling axis and together forming a drum-shaped body. At each end of the casing is a central aperture 22 by which air is admitted to the eyes of the impellers. Each impeller 20 discharges into a series of like delivery ducts uniformly distributed around the casing. Each duct has an inlet portion 23 corresponding to part of the diffuser or volute chamber of a conventional centrifugal fan and leading radially outwards. An intermediate portion of each duct leads helically outside the rotary member to an outlet port 24 directing air radially inwards onto the finned rim of the rotary member. The two series of ducts are symmetrically arranged, and each cools one half of the width of the rim. Between the outlet ports of the ducts the casing is provided with exhaust ports 25 by which the heated air is discharged radially outwards. The exhaust ports are provided with gauze covers 28.

The rim 16 of the rotary member and the hollow cylindrical armature 15 are divided into two parts and each half-rim is shrunk onto its re-

spective half-armature the two parts being locked together by hard-drawn copper rivets such as 26 fitted in holes bored in the axial direction through the half-armatures and through radially depending integral flanges on the half-rims. The two half-assemblies are fastened together by bolts such as 27 also fitted in holes bored in the axial direction through the armature 15 and the radially depending flanges on the rim 16. With the specified combination of materials, there is considerable latitude in design in the ratio of the axial dimensions of the light-alloy and iron parts accommodating the rivets; nevertheless the rivets do not work loose as a result of expansion and contraction of the parts due to variations in 15 temperature.

I claim:

1. A coupling for use as clutch or brake for transmitting or restraining rotary motion, and of the kind having a rotary member which is heated 20 as a result of operation of the coupling and which is accommodated in a fixed casing, the rotary member being provided at at least one of its sides with impeller vanes co-operating with a centrifugal fan chamber formed in the side of the fixed casing, the fan chamber being provided with a plurality of delivery ducts distributed around the casing and having outlets shaped to discharge air radially inwards against the periphery of the rotary member, and the casing 30 being provided with exhaust ports which are distributed around the casing in alternation with the outlets of the delivery ducts whereby the air discharged radially inwards against the periphery of the rotary member moves circumferentially of the rotor during its passage from the delivery ducts to the exhaust ports.

2. A coupling for use as a clutch or brake for transmitting or restraining rotary motion, and of the kind having a rotary member which is heated as a result of operation of the coupling 40 and which is accommodated in a fixed casing, the periphery of the rotary member being provided with circumferentially disposed cooling fins, the rotary member being provided at at least one of its sides with impeller vanes co-operating with a 45

centrifugal fan chamber formed in the side of the fixed casing, the fan chamber being provided with a plurality of delivery ducts distributed around the casing and having outlets shaped to discharge air radially inwards against the periphery of the rotary member, and the casing being provided with exhaust ports which are distributed around the casing in alternation with the outlets of the delivery ducts whereby the air discharged radially inwards against the periphery of the rotary member moves circumferentially of the rotor during its passage from the delivery ducts to the exhaust ports.

3. A coupling as claimed in claim 1 and of the electromagnetic type, the rotary member including an annular armature and being built up from a drum of a material of relatively high heat conductivity, carrying the impeller vanes and provided with integral circumferential cooling fins, this drum being shrunk onto the annular armature.

4. A coupling as claimed in claim 3 wherein the drum has a cylindrical bore into which the annular armature is fitted, the armature being locked to the drum by rivets, consisting at least largely of copper and in a hard-drawn condition, disposed parallel to the coupling axis through bores in an end wall of the drum and in the armature.
